UNITED STATES PATENT OFFICE

165,363

CHRISTMAS TREE TRIM OR SIMILAR ARTICLE

Jack Burnbaum, Watertown, Mass.

Application November 27, 1950, Serial No. 13,143

Term of patent 14 years

(Cl. D29—1)

To all whom it may concern:

Be it known that I, Jack Burnbaum, a citizen of the United States, residing at Watertown, in the county of Middlesex, in the Commonwealth of Massachusetts, have invented a new, original, and ornamental Design for a Christmas Tree Trim or Similar Article, of which the following is a specification, reference being had to the accompanying drawings, forming a part thereof, in which:

Figure 1 is a front elevational view and Figure 2 is a side elevational view of a Christmas tree trim or similar article embodying my new design.

I claim:

The ornamental design for a Christmas tree trim or similar article, substantially as shown.

JACK BURNBAUM.
